(57) **CLAIM**

The ornamental design for a bottle cap, as shown and
described.

DESCRIPTION

FIG. 1 is a front top perspective view of a bottle cap showing
our new design;

FIG. 2 is front lower perspective view thereof;

FIG. 3 is a front view thereof;

FIG. 4 is a rear view thereof;

FIG. 5 is a top view thereof;

FIG. 6 is a bottom view thereof;

FIG. 7 is a right side view thereof; and,

FIG. 8 is a left side view thereof.

The broken lines shown in the figures are for the purpose of
illustrating portions of the bottle cap and form no part of the
claimed design.

1 Claim, 5 Drawing Sheets
